UNITED STATES PATENT OFFICE

EDWARD H. SWINDELL AND FRANK W. BROOKE, OF PITTSBURGH, PENNSYLVANIA,
ASSIGNORS TO WILLIAM SWINDELL & BROS., OF PITTSBURGH, PENNSYLVANIA, A
CORPORATION OF PENNSYLVANIA

FURNACE AND METHOD OF OPERATING THE SAME

Application filed January 29, 1923. Serial No. 615,511.

- The present invention relates broadly to furnaces and the method of operating the same, and more particularly to heating or annealing furnaces.
- 5 At the present time, it is customary to construct heating or annealing furnaces for straight combustion closed annealing, for electric open annealing and for continuous annealing.
- 10 Straight combustion closed annealing is objectionable to some extent by reason of the lack of uniformity of temperature within the furnace thereby affecting the uniformity of the product, and by reason of the warping of 55 the annealing boxes. For this reason, it is being gradually replaced by electric open annealing. Due, however, to the comparatively high cost of electric current, such furnaces have been largely confined to the 60
- 15 treatment of special sheets and compositions 65 in connection with which absolute uniformity is essential. With continuous annealing furnaces, there is obtained continuous operation, muffle firing at an economical rate, partial cooling of the annealed material within the furnace and preheating of the combustion air. In furnaces of this latter type as now constructed, it is customary to 70 load the cars at one end and unload them at the opposite end. In some cases the empty cars are returned outside the furnace, thereby wasting a considerable portion of their sensible heat. Where the empty cars have been 75 returned through the furnace, the heat of the material unloaded at the discharge end is lost. Where the cars have been passed in opposite directions through the furnace in such manner that the heated or outgoing cars 80 radiate heat to the cold or incoming cars, two operating stations at opposite ends of the furnace have been required for loading and unloading. Furthermore, the construction 85 has not been such as to secure high thermal efficiency.
- 40 By the present invention there is provided an improved construction which combines certain of the advantageous features of the previous types of furnaces referred to herein in such manner that high thermal efficiency 90 is obtained together with uniformity of 95 temperature and simplicity of operation with a minimum amount of scaling and warping.
- In the accompanying drawings, there are illustrated certain preferred embodiments of the present invention, the drawings being largely diagrammatic as they do not define the limits of our invention, it being contemplated that changes may be made in the construction and operation disclosed herein without departing from the spirit of the invention or scope of our broader claims. 60
- In the drawings, Figure 1 is a horizontal sectional view through a furnace constructed in accordance with the present invention and diagrammatically illustrating the construction and operation thereof; 65
- Figure 2 is a transverse sectional view on the line II—II of Figure 1; 70
- Figure 3 is a transverse sectional view on the line III—III of Figure 1; 75
- Figure 4 is a sectional view corresponding to Figure 3, and illustrating a slightly modified form of furnace; 80
- Figure 5 is a sectional view, corresponding to Figure 2, of a furnace of the type partly illustrated in Figure 4; and 85
- Figure 6 is a diagrammatic cross-sectional view of a modified form of furnace. 90
- The present invention provides a furnace in which a maximum saving of heat is effected and in which the advantages both of a combustion furnace, due to its low operating cost, and of an electric furnace, due to its uniformity of temperature, are combined. One method of obtaining the desired results is 95 illustrated in Figures 1, 2 and 3 in which there is shown a furnace 2 having its walls, roof and foundation of any suitable material. At the charging end of the furnace there is provided a charging chamber 3 having a charging door 4. Within this chamber may be arranged a system of tracks 5 permitting a charged car to be moved either laterally from the charging opening or longitudinally therethrough. 100
- A charged car is adapted to be fed from the charging chamber 3 into the preheating chamber 6. Within this chamber there may be arranged any desired number of tracks, three sets being illustrated in this particular

form. The entering car is adapted to be placed on either of the outside pairs of tracks. Communication between the charging chamber 3 and the preheating chamber 6 may be cut off at will be a suitable system of doors 7, as is customary in this art.

Within the preheating chamber 6 the entering material is subjected to the heat given off by previously heated material and the carriers as will be more fully pointed out hereinafter. This material is then adapted to pass from the preheating chamber 6 into one or the other of the independent furnaces 8. These furnaces may be of any well known construction, but may advantageously be heated by regenerative principles of the type shown, for example, in Swindell Patent No. 624,401 of May 2, 1899. While traveling through the furnaces, the temperature of the cars, the material thereon, and the annealing boxes, is brought to approximately the desired point. At this temperature the material may leave the combustion furnaces, passing outwardly therefrom into a transfer chamber 9. Within this chamber, the cars are moved laterally onto a central track and may then be passed into an electrically heated furnace 10. This furnace is illustrated as having electrical heating elements 11 adjacent each side thereof although it will be apparent that the arrangement of the heating elements and the construction thereof may be varied in accordance with the requirements of the particular furnace being installed.

While the specific arrangement of the combustion and the electrically heated furnaces is immaterial, it has been found very desirable to arrange the same in side-by-side relationship whereby there is a common wall between the respective chambers. In this manner, the comparatively inexpensive fuel utilized for maintaining the temperature within the combustion furnaces is effective for assisting in the maintenance of the temperature within the furnace 10. In accordance with the best practice, the temperature within the furnace 10 is preferably maintained as nearly uniform as possible. In this manner uniform results may be obtained. It will be apparent that by utilizing electricity as the heating means, such a control is easily and automatically effected. When an electric furnace is holding its temperature constant, the consumption of power during the period of operation represents the heat loss through the furnace lining. This loss is a function of the lining area and of the difference in temperature between the inside and outside of the lining. It is well recognized that the loss due to this difference in temperature varies as the fourth power of the temperature difference. It will readily be seen, therefore, that if the temperature outside the lining of the furnace 10 can be kept the same as that inside the lining, there will be no loss

of heat and therefore no expenditure of power. The walls 12 intermediate the combustion furnaces 8 and the furnace 10 are directly subjected to the temperature within the furnaces 8 and thereby the temperature difference on opposite sides of this lining is kept at a minimum. In order to minimize heat losses through the roof 13, there may be provided any desired amount of insulating covering 14. This arrangement therefore provides for accurate and automatic temperature control within the chamber 10 together with an ideal atmospheric condition therein both of which are obtained at an absolute minimum expenditure of power.

The substantially uniform power consumption within the furnace 10 is also very desirable when it is considered that the charge for electricity is considerably decreased where a constant load factor is maintained.

After the material has been subjected within the furnace 10 to the desired temperature for the required length of time, it may pass outwardly therefrom on the central track within the preheating chamber 6. Within this chamber, as clearly shown by Figure 3, there are no intermediate longitudinally extending partitions. The heat from the car and its charge is therefore permitted to radiate freely in substantially all directions. It is obviously impossible to commercially effect any material saving of the heat radiated downwardly although the amount of radiation in this direction may be minimized by the provision of sand seals 15, as is customary in the art. The heat radiated laterally is directly absorbed by the incoming cars on the outer tracks, while the heat radiated upwardly may be utilized for preheating air within longitudinally extending pipes 16. These pipes in turn may supply the combustion air for the furnaces 8 whereby preheated air is utilized and a considerable saving thereby effected.

With certain classes of material, it is desirable that the period required for bringing the incoming material to the desired temperature should be substantially twice as long as the period required for the actual heat treating operation. Thus, for example, if the material leaves the preheating chamber at a temperature of 400° F., 20 hours may be necessary to raise the temperature to the desired point, say 1550° F. within the furnaces 8. Within the furnace 10 there will be maintained a temperature of 1550° F., but it will only be necessary to keep the material within this furnace for approximately ten hours. As there are two tracks supplying material to the furnace 10, it will be apparent that the travel through this furnace is twice as fast as the travel through the furnaces 8, thereby automatically providing the desired time intervals.

It will be understood that the preheating chamber and the furnaces 8 and 10, respectively, may be separated by movable closures 116 of any desired construction, and that the transfer chamber 9 may in turn be 5 separated from the furnaces by movable closures 117. The closures 117 are very desirable in that they prevent the passage of any considerable amount of sulphur from the combustion furnaces into the electric furnace 10. This increases the length of life 10 of the electric heating elements, as they are thus in effect protected from the action of the sulphur.

It will be understood that if it were desirable to shorten the combustion heating period and lengthen the electric maintaining period, the central furnace could be heated by combustion and the two outer furnaces could be heated electrically. The 20 material would then be fed into the central furnace and thence into either of the two side furnaces. Also, if it is desired to provide uniform periods of heating and electric maintaining, the operation may be carried out by the use of equal numbers of combustion furnaces and electric furnaces.

In Figures 4 and 5 there are illustrated transverse sectional views through a modified form of installation having outside combustion furnaces 8', each with a single pair of tracks and a central electrically heated furnace 10' with two pairs of tracks. In operating this installation, it will be apparent that the electric maintaining and heating periods are of the same length, as each combustion furnace 8' may supply a single track within the furnace 10'. On the other hand, a single combustion furnace 8' might be utilized in some cases for keeping both 40 of the tracks within the furnace 10' filled. This operation would provide a heat maintaining period substantially twice as long as the heating period.

In an installation of this character, the preheating chamber 6' preferably has in addition to the air pipes 16, pipes 17 adapted to lie between the cars on the center tracks. In this manner, the radiated heat 50 from between the cars is utilized for pre-heating the air. These air pipes may supply air through suitable connections, not shown, to the air intakes 18 for the regenerative combustion system. This regenerative system is here illustrated as being of the 55 type shown in the Swindell patent before referred to, although this construction is illustrative only.

The preheating chamber not only serves 60 to reclaim the heat radiated from the heat treated material in three different directions, but also serves the purpose of cooling the material to a temperature at which it can be exposed to the atmosphere.

65 Unless it is desired to load the cars di-

rectly at the rolling mill, the sensible heat of the cars and covers may always be reclaimed by immediately removing the treated work from the outgoing cars, reloading the cars and immediately charging the same back into the preheating chamber.

In some instances, it may be desirable to cover the annealing boxes and the cars with a high carbon pitch. As the volatile portions of the pitch burn out, there is left a heavy sooty deposit. This deposit in some instances has the effect of cutting down scaling and warping of the cars and the annealing boxes. Also, the burning pitch generates a considerable amount of heat which would be retained to a large extent by the cars and the annealing boxes.

In Figure 6 there is shown an installation comprising independent furnaces 21, 22 and 23. Certain of these furnaces may be of the combustion type, as, for example, furnaces 21 and 23; while the remaining furnace may be electrically heated. With this arrangement, the combustion furnaces 21 and 23 would tend to maintain a high heat in the common furnace walls 24 and 25, thereby decreasing to a minimum the temperature difference on opposite sides of these walls. In order to secure a substantially similar result with the top wall 26, there may be provided a supplemental roof 27 providing a chamber 28. This chamber, in order to secure the desired circulation of heat within the combustion furnaces, may have ported partition walls 29. By such a construction the combustion furnaces substantially enclose, and thereby materially restrict radiation of heat from, the electric furnace or furnaces. This principle is applicable to all of the various forms of installations disclosed herein.

The advantages of the present invention arise from the provision of an improved installation and a method of operating the same, whereby it is possible to utilize both inexpensive and comparatively expensive fuels at a minimum of cost.

Further advantages arise from the simplicity of operation of the installation, the decreased scaling and warping of the annealing boxes of material to be treated, partly due to the fact that they are gradually brought up to temperature, and the high thermal efficiency of the installation.

We claim:

1. In a method of annealing, the steps consisting in first heating the shapes to be annealed in a chamber heated by combustion, conveying said shapes out of said chamber, transferring the shapes laterally and then into a second chamber electrically heated, 120 and further heating said shapes in said second chamber.

2. In a method of annealing, the steps consisting in first heating the shapes to be annealed in a chamber heated by combustion, 125

conveying said shapes out of said chamber and into a second chamber electrically heated, maintaining said chambers out of direct communication, further heating said shapes in said second chamber, and utilizing 5 the heat in the first chamber to lower the heat loss from the second chamber.

3. In a method of annealing, the steps consisting in first heating the shapes to be annealed in a chamber heated by combustion, 10 conveying said shapes out of said chamber and into a second chamber electrically heated, maintaining said chambers out of direct communication, further heating said shapes in said second chamber, and minimizing 15 the temperature variant between the inside of said second chamber and the outside thereof by the heat of the first chamber.

4. In a method of annealing, the steps consisting in first heating the shapes to be annealed in a chamber heated by combustion, 20 conveying said shapes out of said chamber and into a second chamber electrically heated, further heating said shapes in said second chamber, and moving the shapes at different rates of speed through each of said chambers.

5. In a method of annealing, the steps consisting in first heating the shapes to be annealed in a chamber heated by combustion, 30 conveying said shapes out of said chamber and into a second chamber electrically heated, further heating said shapes in said second chamber, moving the shapes at different rates 35 of speed through each of said chambers, and minimizing the temperature variant between the inside of the second chamber and the outside thereon by means of the heat of the first chamber.

6. In a method of annealing, the steps consisting in charging shapes into a furnace at one end first heating the shapes to be annealed in a chamber heated by combustion, conveying said shapes out of said chamber and into a 45 second chamber electrically heated, reversing the direction of travel of the shapes between said chambers, further heating said shapes in said second chamber, and then passing the finally heated shapes from said second chamber at the charging end of the furnace in proximity to fresh shapes to be annealed.

7. In a method of annealing, the steps consisting in first heating the shapes to be annealed in a chamber heated by combustion, 55 conveying said shapes out of said chamber and into a second chamber electrically heated, further heating said shapes in said second chamber, then passing the finally heated shapes from said second chamber in proximity to fresh shapes to be annealed, and minimizing the temperature variant between the inside of the second chamber and the outside thereof by means of the heat in the first-mentioned chamber.

8. In a method of annealing, the steps con-

sisting in first heating the shapes to be annealed in a chamber heated by combustion, conveying said shapes out of said chamber and into a second chamber electrically heated, further heating said shapes in said second chamber, and then passing the finally heated shapes out of said second chamber in proximity to and in the opposite direction to the movement of fresh shapes to be annealed.

9. In a method of annealing, the steps consisting in first heating the shapes to be annealed in a plurality of chambers heated by combustion, conveying said shapes out of said chambers and into a second chamber electrically heated, further heating said shapes in said second chamber, and then passing the finally heated shapes out of said second chamber between fresh shapes to be annealed going into first mentioned chambers and in a direction opposite to the direction of movement of said fresh shapes.

10. In the method of treating material, the steps consisting of annealing said material, effecting movement of the annealed material in proximity to and between adjacent lines of material to be annealed and in heat conducting relationship to said lines of material, and moving the material to be annealed at a rate of speed different from the speed of movement of the annealed material.

11. In a heat treating furnace, a high temperature heating chamber, electric heating means therefor, a plurality of low temperature heating chambers contiguous thereto and on opposite sides thereof, said low temperature heating chambers being in heat conducting relationship to the high temperature heating chamber for minimizing the temperature variant between the inside of the high temperature heating chamber and the outside thereof whereby heat losses from the high temperature heating chamber are minimized, and combustion means for heating the low temperature heating chambers.

12. In a heat treating furnace, a high temperature heating chamber, electric heating means therefor, a plurality of low temperature heating chambers contiguous thereto and on opposite sides thereof, said low temperature heating chambers being in heat conducting relationship to the high temperature heating chamber for minimizing the temperature variant between the inside of the high temperature heating chamber and the outside thereof whereby heat losses from the high temperature heating chamber are minimized, and combustion means for heating the low temperature heating chambers, there being one closure wall common to all of said chambers.

In testimony whereof we have hereunto set our hands.

EDWARD H. SWINDELL.
FRANK W. BROOKE.
